UNITED STATES PATENT OFFICE.

SAMUEL THACKER, OF NOTTINGHAM, COUNTY OF NOTTINGHAM, ENGLAND.

IMPROVEMENT IN STEAM AND OTHER BOILERS.

Specification forming part of Letters Patent No. 222,429, dated December 9, 1879; application filed July 21, 1879; patented in England, August 23, 1878.

To all whom it may concern:

Be it known that I, SAMUEL THACKER, of the town and county of Nottingham, England, have invented new and useful Improvements in Steam and other Boilers, which improvements are fully set forth in the following specification, reference being had to the accompanying drawings.

The invention has for its object improvements in steam and other boilers, whereby perfect combustion is obtained, and, consequently, no smoke is allowed to escape from the furnace.

The invention is fully described with reference to the accompanying drawings, in which like parts are marked with similar letters of reference.

Figure 1 is a vertical section. Fig. 2 is a horizontal section on the line 1 1 of Fig. 1. Fig. 3 is a partial vertical section on the line 2 2 of Fig. 1, representing an upright boiler constructed according to my invention. Fig. 4 is a partial vertical section representing my improved boiler with a different construction of grate. Fig. 5 is a cross-section on the line 3 3 of Fig. 6, which latter is a longitudinal section of a horizontal boiler with my invention applied thereto.

Upright boilers constructed according to my invention may be of circular section, with a square or rectangular fire-box; but I preferably construct them rectangular or square throughout, as represented in the accompanying drawings at Figs. 1 to 4, inclusive.

The boiler is formed with an outer shell, *a*, and an inner shell, *b*, secured and riveted together, as represented in the drawings, or in other convenient and effectual manner. The inner shell, *b*, terminates with a suitably-shaped fire-hole, *c*, at the top of the boiler, which I ordinarily leave open, as shown, but which may be provided with any suitable door or cover capable of admitting air to the fire, as may be found desirable. The boiler is also fitted with apertures and air-tight doors, one (marked *d*) being placed immediately above the grate to facilitate the cleaning out of the fire, the other (marked *e*) being placed at the bottom of the boiler, for the purpose of enabling the ashes to be removed when required.

A diaphragm, *f*, made in the form of a flat tube, runs transversely across the inner shell,

b. This diaphragm is so constructed as to leave an internal water-space, whereby the heating-surface of the boiler is greatly increased. It is well stayed with copper rivets or stays, as will be well understood.

Brass or other water-tubes *g* run across the inside shell, thereby connecting the water-spaces on opposite sides of the boiler together, thereby greatly extending the heating-surface of the boiler. The tubes *g* are screwed at one end and put through clear-holes in the outer shell. They are then screwed into one side of the inner shell and expanded to fit steam-tight into the opposite side of the inner shell. The hole in the outer shell is tapped to receive a screw-plug, *h*. These plugs *h* have to be withdrawn to clean out the tubes, and to remove and replace them for renewal or repair.

In the arrangement represented at Figs. 1, 2, and 3, the grate or fire-bars are formed of water-tubes *i*, which are reduced at one end to leave sufficient strength of boiler-plate between them; or they may be of equal diameter throughout and thick boiler-plates used. These tubes *i* are passed through holes afterward closed with other screw-plugs, *h*, and are screwed into the inner shell of the boiler at the one end, and are expanded to fit steam-tight at the opposite end, and they are inclined to the horizontal to facilitate circulation of the water therethrough.

Immediately over and resting on the tubes *i* are placed loose or movable bars of metal or fire-brick *i'*, to protect the water-tube bars against accident when raking out the fire and against the extreme heat of the latter. The fire-bars *i'* are in a suitable position above the diaphragm-plate, and at or near the top of the water in the boiler.

The uptake or flue for taking away the products of combustion is placed on the opposite side of the diaphragm to that on which the products of combustion first act.

In the arrangement represented at Fig. 4, the grate shown is formed of a water-chamber, *j*, communicating by tubes *j'* with the water-spaces between the shells *a b* of the boiler, and I pass tubes *j''* vertically through such hollow furnace-bottom *j* to allow the products of combustion to pass therethrough. These tubes *j''* I prefer to form taper and to fix the smaller

end at the top, so as to facilitate the passage and clearance away therefrom of any cinders or clinkers which may pass into the same.

Immediately above the fire bars or grate, and at various distances below the same, are placed short tubes *k*, all of which communicate with the outer atmosphere, while those above the fire-grate conduct air to the fire, and those below conduct air to the flame and products of combustion below the grate to insure perfect combustion.

The boiler may be set upon a bed-plate or upon masonry, as desired.

The action of boilers, such as those represented at Figs. 1, 2, 3, and 4, is as follows: The space below the grate is divided into two chambers by the diaphragm. The fire is made on the fire bars or grate, and the lower chamber being in connection with the chimney, a current of air would be immediately caused to descend through the fuel. The heat and products of combustion would pass downward round and across some of the tubes *g*, and would play on the sides of the inner shell, *b*, and on one side of the diaphragm. They would then turn round the bottom end of the diaphragm, and would rise to and pass away by the outlet *x*, as indicated by the arrows, and in doing so would act upon the second side of the diaphragm, as also upon other of the tubes *g* and upon the sides of the inner shell, *b*.

In applying my invention to horizontal Lancashire, Cornish, or tubular boilers, and as represented at Figs. 5 and 6, which are, respectively, a cross-section and a longitudinal section of a horizontal boiler constructed according to my invention, I place the fire-grate in a vertical rectangular or square fire-box, *l*, and the flame and products of combustion pass downward between the fire-bars *i*, or through the hollow grate *j*, as the case may be, and along a flue, *m*, formed within the body of the boiler, and extending to, or nearly to, the opposite end thereof, and then returning to the front or furnace end of the boiler, where the

products of combustion pass away through the outlet-aperture *x* into the exterior flue, which may be carried along the sides and underneath the boiler. A water-space or diaphragm, *f*, divides the two parts of the flue *m*, and water-tubes *n*, passing through or across the flue *m*, connect the water-spaces above and below the flue *m* with the central divisional water-space or diaphragm, *f*, thereby assisting circulation of the water and the absorption of heat from the products of combustion as the latter pass across and around the tubes *n* in their passage through the flue *m*.

The flue *m* is formed of the shell *b* and the sides of the central divisional water-space, *f*; and I would remark that the flue *m* may, if desired, be extended so as to return again to the rear end of the boiler, and, if desired, back again, suitable water-spaces or diaphragms *f* being employed, as required, suitable internal supports in such cases being employed to secure the flues *m* in position.

In boilers constructed according to my invention ignition takes place, as usual, above the grate; but the products of combustion, instead of passing away, as heretofore, either upward or along the length of the furnace, are caused to pass downward through the intense heat of the fire, whereby complete combustion is effected.

Having thus described the nature of my said invention, and the mode in which I carry the same into effect, I would have it understood that what I claim is—

A boiler having inner and outer shells, vertical fire hole or box, hollow grate-bars, apertures and tubes traversing the space between the shells and conveying air to various parts of the interior, diaphragm or water-space, cross-tubes, and smoke-outlet, substantially as and for the purpose set forth.

SAML. THACKER.
